W. J. WHITACRE

ELECTRIC LIGHTING FIXTURE

Filed Sept. 8, 1924

INVENTOR

William J. Whitacre,
BY John Tobias Jones,

ATTORNEY.

UNITED STATES PATENT OFFICE.

WILLIAM J. WHITACRE, OF CINCINNATI, OHIO.

DESIGN FOR AN ELECTRIC-LIGHTING FIXTURE.

Application filed September 8, 1924. Serial No. 10,706. Term of patent 3½ years.

To all whom it may concern:

Be it known that I, WILLIAM J. WHITACRE, a citizen of the United States of America, residing at Cincinnati, in the county of Hamilton and State of Ohio, have invented a new, original, and ornamental Design for Electric-Lighting Fixtures, of which the following is a specification, reference being had to the accompanying drawing, forming part thereof.

In the said drawing, the view presented is a front elevation of a wall bracket or a two-branch candelabrum for electric-lighting fixtures embodying my new and original design, the essential or predominating feature of which is the representation of a

thistle, that includes the flower, the stem and the leaves scattered or spread throughout more or less of the surface of the body-portion or main-plate of the wall-bracket and, also, with a single flower-of-the-thistle hanging pendent from the bottom of each of the lateral or side pair of imitation-candle supporting-arms. The fixture is otherwise distinctly armorial in its character or conspicuously-attracting front display.

I claim:—

The ornamental design for an electric-lighting fixture, as shown and described.

WILLIAM J. WHITACRE.
